Primary Examiner—Nelson C. Holtje*Assistant Examiner*—Monica A. Hannon*Attorney, Agent, or Firm*—Terry M. Gernstein**[57] CLAIM**

The ornamental design for a shower curtain reinforcing element, as shown and described.

DESCRIPTION

FIG. 1 is a side perspective view of the shower curtain reinforcing element showing my new design;

FIG. 2 is a front elevational view thereof, the rear being a mirror image of the front shown in FIG. 2;

FIG. 3 is a side elevational view thereof, the side opposite being a mirror image of the side shown in FIG. 3;

FIG. 4 is a top plan view thereof; and,

FIG. 5 is a bottom view thereof.

FIG. 3.

FIG. 2.

FIG. 4.

FIG. 5.
